UNITED STATES PATENT OFFICE

2,142,612

BOILER

Charles E. Lucke, New York, N. Y., assignor to
The Babcock & Wilcox Company, Bayonne,
N. J., a corporation of New Jersey

Original application January 3, 1927, Serial No.
158,470. Divided and this application August
11, 1930, Serial No. 474,678. Renewed May 19,
1934

12 Claims. (Cl. 122—235)

This invention relates to steam boilers of the forced circulation type in which a circulating pump is employed for insuring proper circulation of the water through the tubes of the boiler, and 5 this application is a division of my application Serial No. 158,470, filed January 3, 1927.

An object of this invention is to provide a boiler of the type set forth having improved features of construction as will be more readily 10 understood from the following description.

In the drawings Fig. 1 is a transverse sectional view through the boiler furnace showing a boiler arrangement constructed in accordance with one embodiment of this invention.

15 Fig. 2 is a transverse sectional view on the line 2—2 of Fig. 1;

Fig. 3 is a sectional view through a combined steam turbine and centrifugal pump in the storage chambers employed in connection with the 20 arrangement illustrated in Fig. 1;

Fig. 4 is a partial sectional view taken on the line 4—4 of Fig. 3;

Fig. 5 is a view similar to Fig. 1 illustrating a 25 different arrangement; and

Fig. 6 is a perspective view showing the arrangement and correlation of the boiler tubes in the furnace.

As illustrated, the boiler is provided with a feed 30 pump having a water cylinder 1 and a steam cylinder 2. The exhaust steam passes into the coil 3 located in the water tank 4 where it is condensed. Suction tube 5 leads from the feed water tank to the water cylinder 1 and feed water is supplied to the tank delivery line 6 that 35 is connected with any desired source of supply and controlled by a suitable float 7. A feed water delivery line 8 connects the water cylinder of the feed pump with the boiler.

As illustrated in Fig. 1, the circulation of the 40 unvaporized water through the boiler is produced by a centrifugal or screw pump which is combined with the steam separator that is directly connected to a steam turbine driven by a part or all of the steam generated by the boiler after such 45 steam has become dry through freeing it of liquid. As shown, the feed water passes from the feed water pump through a pipe 8 to a header 170 extending vertically upward, thence through horizontal tubes 171 extending across the furnace 50 flue to a vertical header 172 and through connected pipes 173 and 174 to a combined steam and water separator, storage chamber and circulating pump 175 from which the separated steam passes through a pipe 30 to the steam 55 main, a safety valve 42 being associated with the

pipe. The separated water is forced by means of a centrifugal pump hereinafter described through a circulating water delivery line 13 to a distributing header 176. The header supplies water to a row of slag screen tubes 177 leading to a header 178 connected with the bridge wall cooling tubes 179 to a header 180, from which the flow is through connections 181 and 182 to the pipe 174 leading to the steam and water separator. The header 176 also delivers water through connections 183 on each side of the boiler furnace to lower wall headers 184 connected by wall tubes 185 to upper headers 186 from which the steam and water flows to the pipe 174.

The combined steam and water separator and 15 centrifugal pump 175 is illustrated in detail in Figs. 3 and 4. The mixture of steam and water delivered by the pipe 174 enters the tubes through the inlet 190 where it is directed by curved plates 191 downwardly over a baffle 192 into the lower 20 part of the separator. The water collected in the bottom of the chamber is driven by a centrifugal pump 193 through an outlet 194 connected to the circulating water supply line 13. The separated steam passes upwardly, as is generally indicated 25 by the arrows, and flows through turbine 195 the rotor of which is secured by a shaft 196 which is also connected to the rotor of the centrifugal water pump 193. The steam from the turbine 195 passes through a steam outlet 197 to the 30 delivery line 30. The pump and turbine connected shaft 196 is provided with a worm 198 meshing with a worm gear 198' on a shaft 199 arranged to drive a centrifugal governor 199 for 35 controlling a steam by-pass 200 around the turbine, the arrangement being such that the by-pass valve 200 is opened at a predetermined turbine speed to permit the passage of steam to the outlet 197 without having to flow through the turbine 195, by this arrangement all of the power 40 steam is subjected to only a small drop in pressure on the way to the main power use, and through such drop is caused to operate a dry steam motor for driving auxiliaries, one kind of 45 which is shown here as being a pump. This arrangement insures a better system heat balance than would be the case if only a small part of the steam should be taken away and its whole pressure range used for auxiliary purposes. The 50 advantage of this arrangement of using all of the steam with a small pressure drop instead of a small portion with a high pressure drop is greater in small size units, or with very high steam pressures, and it is most valuable when both conditions prevail; by these means and by 55

this method it becomes possible to utilize steam in small high pressure units of greater overall efficiency than is otherwise possible.

- This arrangement is of particular advantage in that it permits the use of small power steam turbines at high pressure for driving auxiliaries, whereas with the usual arrangement of utilizing the entire pressure drop the high pressure of the steam and the small power of such auxiliary drive turbine demands such minute nozzle passages that friction of the steam in passing through the same is prohibitive to the arrangement.

- A float mechanism is attached to a lever 17 connected by a chain 18 to the valve 19 in the steam line 14 leading to the steam cylinder of the feed water pump so that the rate of operation of the feed pump is controlled by the level of the water collected in the separator chamber 175.

- In the modification illustrated in Fig. 5, the feed water passes through the pipe 8 into vertical header 201, thence through a horizontal tube 202 to a vertical header 203 on the other side of the gas outlet flue, thence through tubes 204 and 205 to the combined steam and water separator and circulating pump 175. The unvaporized water from the steam and water separator is forced through a circulating water delivery line 13 to a header 206, and thence to circulating coils which are most clearly illustrated in Fig. 6. The water divides, passing into three headers 207, 208 and 209. From the header 208 the flow is through a row of slag screen tubes 210 to a header 211, thence through vertically disposed tubes 212 to an upper header 213, thence through connections 214, 215 and 216 to the pipe 205 leading back to the steam and water separator. Another part of the water passes from the header 208 through side wall cooling tubes 217 to an upper header 218, and through a second header 219, and wall tubes 220 to header 221, thence through connections 222 and 223 to the steam and water separator.

- Another portion of the water flows from the header 209 through horizontal wall cooling tubes 224 to a vertical header 225, thence through connections 215 and 216 to the steam and water separator. Another portion of the circulating water passes from the header 207 to the vertical header 226, thence through horizontal side wall cooling tubes 227 to a vertical header 228, and thence through the connections 223 and 216 to the steam and water separator.

What I claim as new and desire to secure by Letters Patent is—

1. In a steam generating system, a combustion chamber and flue, steam generating tubes in said combustion chamber, an economizer in said flue, a steam and water separator receiving the discharge from the aforesaid tubes and economizer, a pump delivering water to said system, a turbine and circulating pump within said separator and connected in operative relation, the turbine disposed on one side of the steam and water discharge to said separator and the pump disposed on the other side, the steam released in the separator driving the pump to re-circulate separated water in the system, a connection between the circulating pump discharge and said system, all of the steam released in the separator being directed toward the turbine for operation thereof, and a valve controlled steam by-pass governing the turbine operation.

2. In a steam generating system, a combustion chamber and flue, steam generating tubes in said combustion chamber, an economizer in said

flue, a steam and water separator receiving the discharge from the aforesaid tubes and economizer, a pump delivering water to said system, a turbine and circulating pump within said separator and connected in operative relation, the turbine disposed on one side of the steam and water discharge to said separator and the pump disposed on the other side, the steam released in the separator driving the pump to re-circulate separated water in the system, a connection between the circulating pump discharge and said system, all of the steam released in the separator being directed toward the turbine for operation thereof, a valve controlled steam by-pass governing the turbine operation, and means actuated by the water level in the separator for controlling the amount of new water added to the system by the feed pump.

3. In a steam and water separator, a separating chamber, a turbine at one end thereof and a pump at the other end thereof, the turbine and pump being connected in operative relation, the pump receiving all of the water from the separator and the turbine adapted to normally receive all of the steam from the separator, and a turbine governor in combination with a by-pass directing some of the steam around the turbine when the turbine reaches a predetermined speed.

4. In a steam and water separator, a separating chamber, a turbine at one end thereof and a pump at the other end thereof, the turbine and pump being connected in operative relation, the pump receiving all of the water from the separator and the turbine adapted to normally receive all of the steam from the separator, and a centrifugal governor in combination with a by-pass directing some of the steam around the turbine when the turbine reaches a predetermined speed.

5. A steam generating system comprising a steam generator having a combustion chamber and a heating gas outlet flue, a group of steam generating tubes absorbing radiant heat from said combustion chamber, a group of convection heated tubes located in said outlet flue, a steam and water separating chamber having an inlet receiving the discharge from both of said tube groups, separate steam and water outlets from said separating chamber, a rotary circulating pump positioned in the water space of said separating chamber and arranged to deliver water separated in said chamber directly to said combustion chamber tube group, a feed pump for supplying feed water to said outlet flue tube group only in accordance with the water level in said separating chamber, a turbine located in the steam space of said separating chamber between said inlet and steam outlet and arranged to be actuated by steam passing to said outlet, a driving connection between said turbine and rotary pump, means in said separating chamber below said turbine for separating the incoming steam and water, a steam by-pass around said turbine, and means controlling the amount of steam passing through said by-pass in accordance with the speed of said turbine, whereby the amount of water circulated through said combustion chamber tube group will be controlled in accordance with the amount of steam passing through the turbine.

6. The method of operating a pressure vapor generator having auxiliaries supplying working medium and elements of combustion and with a pressure vapor power take-off having a dry vapor operated auxiliary driver therein which com-

prises drying all of the vapor generated, normally expanding all of the dried vapor through said driver and discharging it to the power take-off, and using the speed of the driver irrespective of demand on the generator to prevent driver speed in excess of a predetermined speed upon generation of vapor beyond the requirements for said selected driver speed.

7. The method of operating a pressure vapor generator having auxiliaries supplying working medium and elements of combustion and with a pressure vapor power take-off having a dry vapor operated auxiliary driver therein which comprises drying all of the vapor generated, normally expanding all of the dried vapor through said driver and discharging it to the power take-off, and by-passing the vapor around the driver in response to a predetermined speed of the driver irrespective of demand upon the generator to prevent driver speed in excess of selected speed upon generation of vapor beyond the requirements for said selected speed.

8. The method of operating a pressure vapor generator having auxiliaries supplying working medium and elements of combustion and with a pressure vapor power take-off having a dry vapor operated auxiliary driver therein which comprises supplying the working medium in relation to the generator heating surface at rates preventing overheating of the surface, drying all of the vapor generated, normally expanding all of the dried vapor through the driver and discharging it to the power takeoff, using the wetness of the working medium leaving the heating surface to regulate the degree of wetness, and using the speed of the driver irrespective of demand on the generator to prevent speed in excess of a predetermined speed upon generation of vapor beyond the requirements for said selected driver speed.

9. In combination, a generator converting liquid into pressure vapor, auxiliaries supplying liquid and elements of combustion, a pressure vapor power take-off, a turbine driver for at least one of the auxiliaries arranged to normally receive all of the vapor generated and discharge it to the power take-off, means drying all of the vapor

entering the turbine, and means responsive to turbine speed irrespective of demand on the generator preventing turbine speed in excess of a selected speed upon generation of vapor beyond the requirements for said selected turbine speed.

10. The method of operating a pressure vapor generator having auxiliaries supplying working medium and elements of combustion and with a pressure vapor power take-off having a dry vapor operated auxiliary driver therein with constantly open orifices for the passage of vapor, which comprises drying all of the vapor generated, and normally expanding and discharging all of the dried vapor through said driver whereby it is continuously expelled into the power take-off in an uninterrupted stream free of pulsation.

11. The method of operating a pressure vapor generator having auxiliaries supplying working medium and elements of combustion and with a pressure vapor power take-off having a dry vapor operated auxiliary driver therein which comprises separating all of the liquid from the vapor generated, normally expanding all of the dried vapor through said driver and discharging it to the power take-off, using the speed of the driver irrespective of demand on the generator to prevent driver speed in excess of a predetermined speed upon generation of vapor beyond the requirements for said selected driver speed, and returning at least some of the separated liquid to the generator.

12. The method of operating a forced circulation pressure vapor generator of small liquid and vapor storage capacity and including pressure vapor driven auxiliaries supplying working medium and elements of combustion and delivering through a power take-off having a dry vapor operated auxiliary driver therein with constantly open orifices for the passage of vapor, which comprises regulating the generator for producing a liquid and vapor mixture in advance of the driver, separating the liquid to dry the vapor, and normally expanding all of the dried vapor in a continuous stream through the constantly open orifices of said driver whereby a non-pulsating stream is maintained at the power take-off.

CHARLES E. LUCKE.
